UNITED STATES PATENT OFFICE.

FREDERIC E. BERTRAND, OF LYNN, MASSACHUSETTS, ASSIGNOR TO UNITED SHOE MACHINERY CORPORATION, OF PATERSON, NEW JERSEY, A CORPORATION OF NEW JERSEY.

POSITIONING DEVICE.

Application filed December 14, 1922. Serial No. 606,879.

This invention relates to devices for positioning soles, shoes or lasts, or other articles of asymmetrical outline and is illustrated as embodied in an insole toe snipping machine of a well known type. The invention has for one object the improvement of machines of this general character by providing accurate means for determining the relative angular positions of the work with respect to the tool which is to operate thereon.

The operating tool of a toe snipping machine consists of several knife edges which are operated by the power of the machine to slit the channel flaps and the outer lips of insoles, especially of insoles for narrow or sharply pointed shoes, and it is important that the work be very accurately positioned in predetermined angular relation to the knife edges. It has been customary to provide these machines with a gage for the end of the toe of the sole, and with a pair of side gages which afford considerable assistance to the operator in determining the correct position of each sole. There is no positive assurance that the operator will position soles of different styles and sizes in any constant manner or that different operators will present the work in the same way.

The present invention provides for increasing the accuracy with which the soles are positioned by providing means for relatively turning the sole and the knife or other tool to place them in predetermined angular relation to one another. Of special utility in a construction of this character, although not necessarily so limited, is an arrangement by which each sole is engaged by a plurality of pairs of connected positioning arms which are movable over a support to engage the edges of a sole at different distances from the end of the toe so as to eliminate all necessity of relying upon the eye of the operator in determining the exact angular position of each sole.

In the illustrated embodiment of the invention a gage is provided for the end of the toe of a sole on a support, one connected pair of arms provided with side gages is arranged to engage opposite sides of the sole adjacent to the toe gage, and a second connected pair of arms formed with side gages is arranged to engage opposite sides

of the sole a somewhat greater distance from the toe gage. By this arrangement if the sole is not placed in the correct angular position on the support it is turned on the support by engagement with the gages carried by the arms into a definitely predetermined angular position. Preferably the two pairs of arms are operated through an equalizing device so that one pair may close further than the other pair according to the contour of the particular sole being operated upon.

Other features of the invention including various specific constructions and novel combinations of parts will be apparent from the following description of the illustrated embodiment of my invention shown in the accompanying drawings in which:

Fig. 1 is a side elevation of so much of a toe snipping machine as is necessary to illustrate my invention;

Fig. 2 is a top plan view of the sole support and the sole positioning means; and

Fig. 3 is a perspective view of the sole support shown in Fig. 2, but with the parts in different positions.

The toe snipping machine shown generally in Fig. 1 comprises a base or pedestal 10, a horizontal, sole supporting table 12 carried thereby, and a snipping tool 14 having several knife edges and which is reciprocated toward and from work on the support 12 by an eccentric on a power shaft 16 controlled by a suitable one-revolution clutch. These parts may be, and are illustrated as being, of a construction identical with those shown and described in United States Letters Patent No. 1,087,578, granted Feb. 17, 1914, on application of John B. Hadaway, in which are fully disclosed knives having respectively straight and V-shaped edges for cutting transversely the insole channel flap and lip.

The insoles to be operated on by the tool 14 are positioned with the ends of the toes against a toe gage 18, the exact angular position of each sole being determined by two pairs of side gages of which one pair comprises rolls 20 carried by upper arms 22 and of which the other pair is provided by the outer ends of lower arms 24. As shown in Figs. 2 and 3, the arms 22 are geared together and are pivotally mounted on two studs 26 projecting vertically from

support 12. The arms 24 are also pivotally mounted at 26 and are geared together as best shown in Fig. 2. One of the arms 22 carries a downwardly extending pin 28 and the opposite arm 24 carries an upwardly extending pin 30, the pins 28 and 30 being engaged by opposite arms of a lever 32, constituting an equalizer, pivoted at 34 on an operating slide 36. Slide 36 is operated to close both sets of arms through equalizer 32 by means of a bell crank lever 38 (Fig. 1), which may be operated by the power of the machine or which may be connected to a suitable treadle (not shown) by means of a treadle rod 40. The outermost position of arms 22 and arms 24 is determined by engagement of one of the arms 24 with a stop 42 mounted in the support 12. The arms are urged at all times toward their outermost, or normal and inoperative, position by a coiled spring 44 connected at one end to one of the arms 22 and at its opposite end to a post 46 carried by the support 12. While the arms 22 are being drawn outward by spring 44, the rolls 20 engage the arms 24 and then carry them to their outermost position.

In operation, a sole is placed on support 12 with its toe in engagement with the toe gage 18 and treadle rod 40 is depressed to move slide 36 rearwardly, that is, away from toe gage 18. Arms 22 and 24 close simultaneously until side gages 20 or the outermost ends of arms 24 engage opposite sides of the sole, whereupon the equalizer 32 permits one set of arms to remain stationary while the other set continues to close until the sole is firmly grasped and positioned by both sets of arms in co-operation with the toe gage 18.

It will be observed that even if the sole is originally placed in an incorrect position the closing arms will operate to turn it in a horizontal plane to bring it into such a position that two lines transversely of the sole arbitrary distances from the end of the toe will be perpendicularly bisected by a line which is at all times equidistant from the side gages 20 and also from the outermost ends of arms 24. This line may be defined as a line parallel to the work table 12 which would pass through a point in the line of contact of the ends of arms 24 and another point in the line of contact of the peripheries of both rolls 20 if the said ends and the said rolls respectively were brought into contact by the turning of the arms inwardly about the studs 26. Since a sole is not a symmetrical object it has no true center line, but for a number of operations, including toe snipping, it has been found convenient to regard such a perpendicular bisector as the center line of the sole and the above described connections operate to place this center line in exact coincidence with a line

perpendicular to toe gage 18 and with respect to which both pairs of side gages are symmetrically arranged.

More particularly a sole will, in most instances, be so placed on the support 12, between the gages of each pair 20, 24 and against the toe gage 18, that it lies more or less out of its correct final position, with respect to the operating tool, both laterally and angularly. In such case, during the movement of the slide 36 to the right, as illustrated, one of the side gages 24, for example, will come into contact with the edge of the sole before its companion gage 24, whereupon the first of these gages will shift the sole laterally over the support 12 into contact with said companion gage, thus centering the engaged portion of the sole. Similarly, if one of the other pair of side gages 20 comes into contact with the sole edge before the other gage of the pair it will then likewise shift the sole laterally. If the equalizing lever 32 were fixed immovably to the slide 36, then, after the gages 24 had gripped the sole, but before the gages 20 had done so, further movement of the slide 36 to the right would be prevented, since the gages 24 could move no further, with the result that the gages 20 could not be brought into gripping engagement with the sole. However, in the illustrated construction, because the lever 32 is pivoted to the slide 36, that lever functions as an equalizing device so that after the sole has been gripped by the gages 24, the turning of the lever 32 permits continued movement of the slide 36 until the sole is further positioned and finally gripped by the other gages 20, thus insuring that each sole, whatever its size or shape, shall be definitely positioned both laterally and angularly on the support 12 and with relation to the tool 14.

Furthermore, this positioning device will maintain the sole in this correct position and resist any lateral pressure unintentionally applied by the operator to the rear end of the sole which tends to turn it out of such correct position.

While my invention has been described as embodied in a toe snipping machine it is not my intention to limit its scope thereby or otherwise than by the terms of the appended claims. The positioning device which has been described above could obviously be readily modified within the spirit of my invention to be utilized in positioning lasts or shoes or other asymmetrical objects, and it is my intention that the term "sole pattern" as used in the claims shall be interpreted as covering such asymmetrical objects, as well as detached soles.

Having described my invention, what I claim as new and desire to secure by Letters Patent of the United States is:—

1. A sole positioning device comprising,

in combination, a flat, horizontal, sole support and a plurality of pairs of connected positioning arms of different lengths pivoted on said support and movable over the support substantially in a horizontal plane to determine the position of a sole on the support by engaging opposite sides of the sole at different distances from one end therof.

2. A sole positioning device comprising, in combination, a flat, horizontal, sole support, two pairs of connected positioning arms of different lengths, a pair of pivot studs for said arms projecting vertically from said support, each stud constituting a fulcrum for one arm of each pair, and common actuating means for moving all of said arms over the support substantially in a horizontal plane to determine the position of a sole on the support.

3. A sole positioning device comprising, in combination, a gage for the end of the toe of a sole pattern, a connected pair of side gages to engage opposite sides of the sole pattern adjacent to the toe gage, a second connected pair of side gages to engage opposite sides of the sole pattern further from the toe gage, and means including an equalizing lever for operating the side gages.

4. A toe-snipping machine comprising, in combination, a toe-snipping knife, a flat sole supported below the knife, a gage for the toe of a sole on the support, a pair of connected side gages pivoted on the support adjacent to the toe gage, a second pair of connected side gages further from the toe support, and equalizing connections for operating the side gages.

5. A positioning device comprising, in combination, a pair of geared-together side gage arms, a pin carried by one of said arms, a second pair of geared-together side gage arms, a pin carried by one of the second pair of arms, and an equalizer engaging said pins and operable to close the arms.

6. A positioning device comprising, in combination, a pair of geared-together side gage arms, a pin carried by one of said arms, a second pair of geared-together side gage arms, a pin carried by one of the second pair of arms, an equalizer engaging said pins and operable to close the arms, and a

stop to determine the open position of the arms.

7. A sole positioning device comprising, in combination, a sole support, a plurality of pairs of connected positioning gages movable into and out of engagement with a sole upon said support, yielding means acting normally to move the gages away from the sole, and means including an equalizing device through which all of the gages may be moved into engagement with the sole.

8. A positioning device comprising, in combination, a work support, a plurality of pairs of connected positioning arms movable relatively to the support to determine the position of a sole pattern on the support both angularly and laterally, and common actuating means for all of said arms constructed and arranged to permit movement of one pair of arms after the other pair has ceased movement.

9. A machine for operating upon a sole pattern comprising, in combination, a support for a sole pattern, a tool designed to operate in definite angular relation to the pattern on said support, and means for turning the pattern on the support to place it in predetermined angular relation to the tool comprising two pairs of movable work engaging members and common actuating means through which all of said members may be moved toward the pattern by the operator, said means including an equalizer which permits movement of one pair of said members independently of the other pair.

10. A machine for operating upon a sole pattern comprising, in combination, a support for a sole pattern, a tool designed to operate in definite angular relation to the pattern on the support, an end gage, a pair of connected side gages adjacent to the end gage, a second pair of connected side gages further from the end gage, and a single mechanism constructed and arranged to be actuated by the operator and including an equalizing device for bringing all four of the side gages into gripping engagement with the sole pattern.

In testimony whereof I have signed my name to this specification.

FREDERIC E. BERTRAND.

CERTIFICATE OF CORRECTION.

Patent No. 1,681,970.

Granted August 28, 1928, to

FREDERIC E. BERTRAND.

It is hereby certified that error appears in the printed specification of the above numbered patent requiring correction as follows: Page 3, line 31, claim 4, for the word "supported" read "support"; and that the said Letters Patent should be read with this correction therein that the same may conform to the record of the case in the Patent Office.

Signed and sealed this 4th day of June, A. D. 1929.

(Seal)

M. J. Moore,
Acting Commissioner of Patents.
